UNITED STATES PATENT OFFICE.

JAMES A. KINNEY, OF LEBANON, PENNSYLVANIA, ASSIGNOR TO BETHLEHEM STEEL COMPANY, OF BETHLEHEM, PENNSYLVANIA, A CORPORATION OF PENNSYLVANIA.

WORK-HANDLING MECHANISM FOR BOLT MACHINES.

Application filed December 29, 1921. Serial No. 525,646.

This invention relates to automatic mechanism for handling the work in a metal turning machine, and is particularly adapted for use with that class of machines which 5 thread or point bolts.

The objects of the invention are to provide an improved carrier mechanism for transferring blanks from a delivery chute or other source of supply to the gripping 10 devices which grip and hold the blanks while the same are being machined; to arrange such carrier so as to avoid the collection of dirt or foreign matter within its moving parts; to provide facilities for adjustment of the gripper jaws; and to provide 15 means for segregating the pieces after they are machined from the scrap cut therefrom.

Other novel features of construction and 20 advantages will hereinafter clearly appear in the detailed description of this invention taken in connection with the accompanying drawings, in which:

Fig. 1 is a plan view of an automatic bolt 25 threading machine, having the improved features applied thereto;

Fig. 2 is a side elevation of the machine as shown in Figure 1, parts appearing in section;

Fig. 3 is a vertical section on the line 3—3 30 of Figure 2, showing the position of the machine when a bolt to be machined is gripped;

Fig. 4 is a view similar to Figure 3, showing the position of the machine when the gripper is in its open position and the ejector chute placed to receive a falling bolt;

Fig. 5 is a vertical cross section on line 5—5 in Figure 2;

Fig. 6 is a detailed sectional view illustrating the adjusting means for the movable 40 gripper jaw.

The machine consists of a frame 10 mounted on legs 11. On the frame, mounted in bearings, is a driving shaft 12 driven by a pulley 13. Keyed to rotate with the driving 45 shaft 12 is a spiral gear 14 meshing with a corresponding gear 15 keyed to the sleeve 16 disposed above and at right angles to the said driving shaft. Integral with or rigidly secured to, the sleeve 16 is a worm 17 which 50 meshes with a worm wheel 18, the latter being fixedly mounted on a cam shaft 19. Aligned with the sleeve 16, and slidingly mounted therein, is the end of a spindle 20. This spindle is mounted in bearings attached 55 to the frame 10, and has fastened to its end

opposite the sleeve a cutting die head 21 or other suitable tool.

The spindle 20 and die head 21 which forms the thread on the bolt blank are operated through a mechanism, not shown, actuated by a cam on the shaft 19 but as such mechanism forms no part of the present invention, it is considered unnecessary to describe the same in detail, but only to show the relation between the cutting die and the 60 feeding and gripping mechanism.

Referring to Figures 1 and 2, mounted to rotate with the shaft 19 is a cam 22, which operates a center board 23 of the hopper 24 through the bell crank lever 25. To one 70 arm of the latter is rotatively attached a roller 26 which is in contact with the face of the cam 22, the end of the other arm of lever 25 being connected to an arm 27 by a connecting rod or spring link hereinafter 75 described. The arm 27 extends at right angles to and is integral with a boss 29 rotatively mounted on the shaft 30 which is mounted in a suitable bearing attached to the hopper 24. Also integral with said boss 80 29 and extending at right angles thereto, is an arm 31 to which is rigidly attached the center board 23, which engages in a slot formed in the bottom of the hopper bowl.

The connecting rod or link between the 85 lever 25 and arm 27 consists of a cylinder 32 (see Fig. 2) open at one end and pivotally connected at its solid end to the arm of the lever 25, the open end being closed by a screw plug 33. Extending centrally 90 through the latter and to the bottom of the cylinder 32 is a rod 34 of smaller diameter than the bore of the cylinder through almost its entire length, but is increased in diameter at its end within said cylinder to slidably fit the latter and also form a shoulder 35. At its end outside the cylinder the rod 34 is threaded and adjustably attached to the end piece 36, which is pivotally connected to the arm 27. Surrounding the rod 100 34 is a coil spring 37, the ends of which bear against the plug 33 and the shoulder 35, respectively. The spring 37 is so designed that the pressure against the shoulder 105 35 keeps the rod 34 in contact with the bottom of the bore of the cylinder 32, during the lift of the center board through the pile of blanks in the hopper 24, but in the event of excessive obstruction caused by a deformed blank or foreign matter between 110

the working surfaces, the crank arm 25 continues its throw and compresses said spring between the shoulder 35 and the plug 33, thereby lengthening the connecting rod 28 5 and eliminating breakage that would follow if the latter was of rigid structure.

The top of the center board 23 is slotted, as at 38, to receive the shanks of the bolt blanks which are lifted by their heads when 10 the said center board pivots from the shaft 30 swinging with a fan-like motion until the top face is flush with the chute 39, which has a slot throughout its length to correspond with the slot 38 in the center board 15 to allow the blanks to slide down to a separator 40, the purpose of the latter being to feed the blanks separately to a carrier, hereinafter described. The aforesaid chute and separator are well known to those versed 20 in the art and are not claimed as new, so a detailed description of these features is considered unnecessary.

Fixed to the cam shaft 19 is a cam 41 which operates a crank 42 to rotate the carrier shaft 43. Also keyed to the shaft 43 is a laterally extending arm 42^a carrying a depending weight 44 from its outermost end, this weight being disposed to keep the roller of the crank 42 in contact with the cam path 30 on the cam 41. The shaft 43 is mounted on the frame 10 in suitable bearings and extends longitudinally of said frame beneath a reciprocating blank carrier, hereinafter described, this carrier being operated by an arm 45 keyed to said shaft, and extending upwardly therefrom.

The carrier includes a slide 46, slidably mounted in a dovetail groove 47 formed in the face of bracket 48, this bracket being 40 rigidly connected to the frame 10 in a position transverse to the longitudinal axis of the shaft 43 and spindle 20. The slide 46 is given a reciprocating motion by means of the arm 45 the upper bifurcated end of 45 which engages a block pivotally mounted on the slide. Journalled longitudinally in said slide 46 is a shaft 49, the ends of which project past the end faces of the slide to receive a cam lever or arm 50 and a bolt carrier 51, 50 respectively. The bolt carrier 51 is keyed to that end of the shaft 49 projecting towards the center line of the frame 10 and the cam lever 50 is keyed to the other end. Immediately above the shaft 49 is an inverted cam groove 52 formed on the underside of an overhanging extension 53 integral with the bracket 48. The groove 52 engages a roller mounted on the end of the lever 50 and is arranged so that when the 55 slide 46 is caused to move along the face of the bracket 48 actuated by the arm 45, the shaft 49 is oscillated or rotated through a predetermined angle. On its upper face 60 the bolt carrier 51 is shaped to form a cradle 51^a which is adapted to receive the bolt

blanks in an inclined position from the chute 39.

When the slide 46 is caused to move towards the center of the machine, the bolt carrier and cradle being attached to the 70 shaft 49, swing through a certain angle operating in unison with the lever 50 following the cam groove 52, and in this manner a bolt which was received at an angle corresponding to that of the chute 39 is moved to a horizontal position and aligned parallel with the axis of the spindle 20 and in a position within the swing of the movable gripper jaw 54 later described. The movements of the parts are, of course, so timed that as the blanks are delivered by the separator 40, they will be received by cradle 51^a 75 of the carrier and delivered in position to be gripped by the movable jaw 54 as said jaw is operated.

It should be stated that the cam groove 52 is so formed that for certain short periods of travel of the slide 46 rotary motion is not imparted to the shaft 49; the first period is to allow the bolt carrier to clear the chute before beginning the angular movement; the second part is after the bolt is in its horizontal position and is being placed within the swing of the movable gripper jaw 54. An apron 46^a integral with the slide and 90 extending therefrom abuts the end of the chute and is of such width as to close the exit from said chute 39 during the passage of the bolt carrier across the machine. The plane of the upper face of said apron coincides with that of the bolt carrier when the latter is in its position before the chute. The overhanging projection 53 on the frame 95 serves to protect the parts beneath from dust and other foreign matter which contributes to the efficiency of the machine.

Also keyed to cam shaft 19 is a cam 55 to operate the gripper shaft 56 through the medium of a crank lever 57 keyed to the end of the gripper shaft. Rotatively mounted 100 on a pin projecting from the lever 57 is a roller in contact with the annular rim of the cam 55. This contact is caused by the overhanging weight of the gripper parts later described, which weight may be supplemented by an overhanging independent weight (not shown). The gripper shaft 56 rotates or oscillates in suitable bearings at either end attached to the frame 10, and has near its end opposite the lever 57 an arm 58 (see Fig. 3) extending at right angles thereto. This arm 58 is bifurcated and has rotatively mounted at its extended end and within the fork, a trunnion block 59, which 110 slidably engages a thrust rod 60, the latter extending downwardly through the block 59 to receive a coil spring 61 which is interposed between the block 59 and an adjustable collar 62 threaded to the lower end of 115 said thrust rod 60. An eye is formed at the 120 125 130

upper end of the rod 60 which is pivotally connected to the center of a toggle joint 63. One of the links of said joint is connected to the frame 10, the other being connected 5 to an extension of the movable gripper jaw 54.

The gripping means consists of a stationary upper jaw 64 attached to the bracket 65 so as to be vertically adjustable and the 10 swinging lower jaw 54 which is pivotally mounted on the bracket 65. The pivot about which the movable gripper jaw 54 swings consists of a bolt 66 having an eccentric head 66^a which serves as a bearing for the 15 jaw 54, the shank of the bolt resting in a bearing integral with bracket 65. The end of the shank extends from the face of the bearing to receive a keyed collar 67, and a further extension is threaded to receive a 20 clamping means such as nuts 67^b and washer. If it is required to adjust the gripper jaw 54 due to the wearing of the gripping surface or for any other reason, the nuts are loosened and a suitable tool is inserted in the holes 25 provided in the collar 67. The latter may then be rotated in either direction rotating the bolt 66, thus changing the center axis of the head relative to the center axis of the bolt blank when the latter is resting against 30 the upper jaw 64. An annular V-shaped projection 67^b on the collar 67 and a corresponding groove in the bracket 65 are formed as a friction device to prevent further movement of the bolt after setting, and 35 during the operation of the machine.

Also keyed to the gripper shaft 56 is a forked lever 68, to the end of which is swivelly attached a connecting rod 69, which in turn is joined by a swivel connection at its 40 other end to a forked lever 70 keyed to and projecting perpendicular from a transverse shaft 71 mounted in bearings attached to the framework of the legs 11, the said swivel connections being of a form commonly 45 known as a universal joint. Keyed to shaft 71 is an arm 72 which carries an ejector chute or receptacle 73 located under the grippers 54, 64 and having a radius of operation within the path of a falling bolt released by 50 said grippers.

It should be understood the various levers are arranged so that when a bolt blank is gripped by the jaws 54 and 64 of the gripping mechanism, the cam 55 pressing over 55 the lever 57 causes the block 59 to press down on the spring 61, which in turn presses down on the collar 52 attached to the lower end of the rod 62, thus spreading the toggle 63. This spreading imparts pressure to the jaw 54 to firmly grip the bolt blank. The block 59 continues to travel after the bolt blank is gripped compressing the spring 61, thus exerting a substantially uniform yielding pressure on the toggle joint 63. The arm 72 is 60 positioned on the shaft 71 relative to the

lever 70 so that when the bolt blank is gripped the ejector chute attached to said arm is swung forward from beneath the bolt so that the scrap cut from the latter falls through an opening in the frame 10 to a pan 70 (not shown). When the gripper jaw 54 is swung in its open position the ejector chute is swung into the path of a dropping bolt, catches it, and on its return to its forward position ejects the bolt into a receiving box 75 (not shown).

It will be noted that all the gears are rotated by a common shaft to give proper timing and uniformity of action. The gripper mechanism and the ejector chute are operated by the same cam which insures positive action between the associated movement of these parts and the blank carrier 51 is operated in proper timed relation with the movable gripper jaw 54 so that such jaw 85 80 grips a blank delivered by the carrier and holds the same while it is operated upon by the tool 21, the carrier in the meantime returning to its position adjacent the chute 39 90 to receive another blank.

In using the device the operator throws bolt blanks promiscuously into the bowl of the hopper 24, and then starts the machine to drive the sleeve 16 and spindle 20 and thereby rotating the cam shaft 19 together with the various cams mounted thereon. The center board 23 passes through the pile of blanks lifting several of the latter by the heads, the shanks falling in the slot provided in the top thereof. When the top face 95 of the center board is flush with the top face of the chute 39, the slot in the former coincides with the slot in the latter, and owing to the incline the bolt blanks gravitate towards the lower end of said chute to the 100 separator 40, operated by a cam 74, keyed to shaft 43 or in any other suitable manner. This separator feeds the blanks one at a time to the extreme end of the chute to be received by the cradle 51^a of the carrier 51. 110 The latter carries the blank across the machine and tilts it to a horizontal position, the blank being lifted out of the cradle by the lower gripper jaw 54 and clamped against the upper jaw 64. The spindle 20 advances 115 the tool or cutting die 21, which retracts after threading the bolt, the gripper jaw opens ejecting the bolt which is caught by the ejector 73. In the meanwhile the bolt carrier has moved over to bring a second blank into position to be gripped by the jaws and during the closing of the latter the ejector swings forward and ejects the bolt 120 previously machined.

Various modifications obviously may be 125 made in the details of the foregoing construction without departing from the spirit of the invention as embodied in the appended claims.

Having thus described the invention what 130

is claimed as new and desired to be secured by Letters Patent is:

1. In a machine of the kind described, in combination, means for gripping a blank and holding the same in fixed position comprising a stationary upper jaw and a movable lower jaw, a chute for delivering blanks, a carrier adapted to receive blanks from said chute and movable to a position beneath the stationary jaw when the movable jaw is retracted to bring a blank in opposed relation with respect to the upper jaw to be gripped by said jaws, means for moving said carrier back and forth between said chute and said gripping means, and means for operating said movable jaw in timed relation with said carrier.
2. In a machine of the kind described, the combination of means for gripping a blank, a chute angularly disposed and laterally offset with respect to the gripping means, a slide movable transversely of the gripping means and of the chute, and a blank carrier on the slide and movable angularly with respect to the slide through an angular distance less than 90° between the plane of a bolt at the delivery end of the chute and the plane of a bolt in the gripping means, whereby the carrier may be brought into proper relation with respect to the chute to receive a blank from the latter and in proper relation with respect to the gripping means to deliver a blank to the latter.
3. In a machine of the kind described, the combination of means for gripping a blank comprising vertically opposed and relatively movable jaws, a chute angularly disposed and laterally offset with respect to the gripping means, a slide movable transversely of the gripping means and of the chute, and a blank carrier on the slide and angularly movable with respect to the slide, whereby the carrier may be brought into proper relation with respect to the chute to receive a blank from the latter and in a position beneath the stationary jaw when the movable jaw is retracted for gripping by the jaws.
4. In a machine of the kind described, in combination, means for gripping a blank and holding the same in fixed position, a chute for supplying blanks and inclined with respect to the gripping means, a slide, a carrier mounted on said slide and movable therewith, means for oscillating the carrier, said carrier being adapted to receive blanks from said chute and deliver the same direct to said gripping mechanism, and means for reciprocating said slide.
5. In a machine of the kind described, in combination, means for gripping a blank and holding the same in fixed position comprising a stationary jaw and a movable jaw, a chute for supplying blanks and inclined with respect to the gripping means, a slide, a carrier mounted on said slide and mov-
- able therewith, means for oscillating the carrier, said carrier being adapted to receive blanks from said chute and transfer the same to a position to be gripped by said jaws, and means for operating said slide and said movable jaw in timed relation.
6. In a machine of the kind described, in combination, means for gripping a blank and holding the same in fixed position, an inclined chute for delivering blanks, said chute being laterally displaced from the gripping means and angularly disposed with respect thereto, a carrier for receiving blanks from said chute and delivering the same direct to said gripping mechanism, means for moving said carrier back and forth between said chute and gripping mechanism and means for moving said carrier into an inclined position when adjacent said chute and into a horizontal position when adjacent said gripping mechanism.
7. In a machine of the kind described, in combination, means for gripping a blank and holding the same in fixed position, an inclined chute for delivering blanks, a carrier for receiving blanks from said chute and delivering the same direct to said gripping mechanism, means for moving said carrier back and forth between said chute and gripping mechanism, a fixed cam, and means connected with said carrier and engaging said cam for moving said carrier into an inclined position when adjacent said chute and into a horizontal position when adjacent said gripping mechanism.
8. In a machine of the kind described, in combination, means for gripping and holding a blank in fixed position, an inclined chute for supplying blanks, a slide, an oscillating member mounted thereon, a carrier connected to said member, an arm also connected to said member, means for reciprocating said slide whereby said carrier is caused to move back and forth between said chute and gripping mechanism, a fixed cam for engaging said arm and oscillating said member, whereby said carrier is caused to occupy an inclined position when adjacent said chute and a horizontal position when adjacent said gripping mechanism.
9. In a machine of the kind described, in combination, means for gripping and holding a blank in fixed position, a tool for operating on the blank so held, a chute for supplying blanks and disposed at an angle to the gripping means, a reciprocating carrier adapted to receive blanks in one position from said chute and deliver the same in another position direct to said gripping means, means for reciprocating said carrier, and means for changing the angular position of the carrier as it moves back and forth between said chute and gripping means to bring said carrier into proper rela-

tion with respect to the chute and to the gripping means.

10. In a machine of the kind described, in combination, means for gripping and holding a blank in fixed position, a chute for supplying blanks, a slide, means for reciprocating said slide, an oscillating member mounted on said slide, a blank carrier secured to said member, said carrier being movable back and forth from said chute to said gripping means as said slide is reciprocated, a projection on the frame of the machine overlying said slide, and having a cam groove on its under surface, an arm secured 15 to said oscillating member and engaging said groove, said cam groove being so shaped as to cause said carrier to receive a blank in one position from said chute and move the blank to a different position when it is 20 delivered to said gripping means.

11. In a machine of the kind described, in combination, a frame, a slide mounted thereon, a projection on said frame overlying said slide and having a cam surface on its under 25 side, an oscillating member mounted on said slide, a blank carrier secured to said member, an arm secured to said member and extending upwardly and engaging said cam surface, a chute for supplying blanks, gripping means for holding the blanks in fixed 30 position while being machined, means for reciprocating said slide whereby said carrier is caused to move back and forth between said chute and gripping means, said cam 35 surface being shaped to cause said carrier to receive the blanks in an inclined position from said chute and move the same into a horizontal position when delivered to said gripping means.

40. 12. In a machine of the kind described, in combination, means for gripping and holding a blank while the same is machined, said means comprising a stationary upper jaw and a movable lower jaw pivoted to swing 45 upwardly toward the upper jaw, a cradle for delivering blanks beneath the upper jaw and within the range of movement of the lower jaw, a device for supplying blanks one at a time to said cradle, means for reciprocating said cradle between said device and 50 said jaws, and means for operating said movable jaw in timed relation with the movements of said cradle.

55. 13. In a machine of the kind described, in combination, means for gripping and holding a blank while the same is machined comprising a stationary upper jaw and a pivoted lower jaw, means for changing the position of the pivot of the lower jaw 60 whereby its relation to the upper jaw may be varied, means for moving said jaw and means for positioning blanks within the range of movement of said lower jaw.

65. 14. In a machine of the kind described, in combination, means for gripping and hold-

ing a blank comprising an upper stationary jaw and a lower movable jaw pivoted to the frame of the machine, an eccentric pivot pin upon which said lower jaw is mounted, said pin being rotatable in its bearings to change 70 the position of said movable jaw relative to the upper jaw, and means for operating said movable jaw.

15. In a machine of the kind described, in combination, means for gripping and holding a blank in fixed position comprising an upper stationary jaw and a lower movable jaw pivoted to the frame of the machine, toggle mechanism for operating said movable jaw and yielding means for operating 80 said toggle mechanism, and means for changing the position of the pivot of the lower jaw whereby its relation to the upper jaw may be varied.

16. In a machine of the kind described, in combination, means for gripping and holding a blank comprising a stationary jaw and a movable jaw, means for operating said movable jaw to grip and release a blank, a tool for operating on the blank held by said jaws, an ejector chute, means operable in timed relation with respect to said jaw operating means for moving said chute into a position to receive the finished blank when the same is released from said jaws and for 90 moving the same into a position to eject such finished blank when said movable jaw is operated to grip the succeeding blank, the last named position of said chute being such that material cut from the succeeding blank by 100 said tool will not be received in the chute.

17. In a machine of the class described, in combination, means for gripping and holding a blank comprising a stationary and a movable jaw, a tool for operating on the 105 blank held between said jaws, a movable ejector chute, driving means, means operated by the driving means for opening and closing said movable jaw, means operated by the driving means for moving said ejector chute to a position beneath said jaws when said movable jaw is opened and for moving the same away from said position when said movable jaw is closed.

18. In a machine of the class described, in combination, means for gripping and holding a blank comprising a stationary jaw and a pivoted jaw, a tool for operating on the blank held by said jaws, a pivoted ejector chute, driving means, means operated by the driving means for opening and closing said pivoted jaw, means operated by the driving means for moving said ejector chute to a position beneath said jaws when said pivoted jaw is opened and for moving the same 120 away from such position when said pivoted jaw is closed, and a common shaft for operating said pivoted jaw and said ejector chute.

19. In a machine of the class described, in combination, means for gripping a blank 130

and holding the same in fixed position, a chute for supplying blanks, a reciprocatory slide, a carrier mounted on the slide and adapted to receive blanks from said chute and deliver the same direct to said gripping means, means for moving the carrier with respect to the slide, and an apron movable

with said slide and adapted to close the exit from the chute when the carrier is moved toward said gripping means.

10

In testimony whereof I hereunto affix my signature.

JAMES A. KINNEY.
